UNITED STATES PATENT OFFICE.

LAWRENCE YORK SPEAR, OF QUINCY, MASSACHUSETTS, ASSIGNOR TO ELECTRIC BOAT COMPANY, OF NEW YORK, N. Y., A CORPORATION OF NEW JERSEY.

TWIN-SCREW SUBMARINE BOAT.

No. 878,752.

Specification of Letters Patent.

Patented Feb. 11, 1908.

Application filed August 1, 1906. Serial No. 328,734.

To all whom it may concern:

Be it known that I, LAWRENCE YORK SPEAR, a citizen of the United States, residing at Quincy, in the county of Norfolk and State of Massachusetts, have invented certain new and useful Improvements in Twin-Screw Submarine Boats; and I do hereby declare the following to be a full, clear, and exact description of the invention, such as will enable others skilled in the art to which it appertains to make and use the same.

The object of the invention is to provide a submarine or submersible boat, having the usual substantially circular cross sectional construction, with twin screws, in order to secure for this type of boat the obvious and well known advantages of double screw propulsion. To effect this object and to avoid out-board bracket bearings for the screw shafts, the stern section of the boat is gradually reduced or diminished vertically, from the substantially circular cross section of the major part of the hull, so as to finally merge, through gradually flattening elliptical cross sections, into a stern frame having substantially parallel sides, within which frame are formed the end bearings for the screw shafts.

Inasmuch as the departure from the substantially circular cross section of the hull will tend to reduce the stiffness of the stern section and to impair its capacity to sustain heavy pressure due to submergence, the invention also contemplates the provision of means for counterbalancing the external pressure of submergence, whenever necessary, so as to completely relieve the stern section from all tendency to collapse when the boat is submerged.

In the accompanying drawings; Figure 1 is a vertical longitudinal section through the aft portion of a submarine boat, showing the application of the invention. Fig. 2 is a horizontal longitudinal section on line 2—2 of Fig. 1. Figs. 3, 4, 5, and 6 are sections taken on lines 3—3, 4—4, 5—5, and 6—6, respectively of Fig. 2.

Referring to the drawings *a* indicates the hull of a submarine or submersible boat, which, according to the generally accepted principles of engineering construction is built upon substantially circular frames *b* covered with shell plating *e*, so that a transverse cross section of the boat taken at any station, is substantially circular. The purpose of this generally circular construction is to render

the hull sufficiently stiff and strong to withstand the heavy pressure of submergence without collapsing. In following the generally circular construction of submarine boats, it has been customary to employ but one screw or propeller for the reason that where the circular construction was carried aft to the stern, two screw shafts could not be installed without having the latter pass through the sides of the hull and be supported in out-board bearings or brackets, which is a construction not suitable for boats of this type.

According to the present invention it is possible to preserve the generally circular cross sectional construction, of the major portion of the hull, and at the same time to provide the boat with twin screws, the shafts of which shall be journaled wholly within the boat. To effect this result the stern section of the boat is given a form which merges or diminishes from the substantially circular cross section of the major portion of the boat, through gradually flattening elliptical cross sections into a stern frame *f* having substantially horizontal sides, and forming the end bearings for the two screw or propeller shafts *g—g*.

The hull is maintained substantially circular in cross section, aft to such point as will admit of the gradual and fair merging of the remaining aft section into the substantially horizontal stern frame. The desired shape of the hull, in this stern section is effected by means of substantially elliptical frames, the major axis of the ellipsis being in a horizontal plane and the vertical axis of the successive frames being reduced so that the frames are gradually flattened or reduced vertically until at the ultimate aft section they merge into the stern frame *f* which has substantially horizontal sides and is provided at its ends with enlarged bosses to form bearings for the propeller and shafts, said frame *f* constituting, in effect, a spectacle frame.

The shell plating *e* is continued aft over the stern section and terminates in the stern or spectacle frame *f*, to which it is riveted. Formed as an integral part of the casting or forging, which constitutes the spectacle frame, are the middle bearings *h* for the steering rudder *i* and the diving rudders *j*. The out-board bearings of the diving rudders *j* are formed in lateral skegs *k—k* formed of plating and secured to the shell as illustrated. The steering rudder *i* finds its out-board

bearings in the bottom skeg *w* and the superstructure *x*, which are common to boats of this type. The screws or propellers *s*—*s* are placed forward of the rudders and therefore assist materially in the steering and diving operations by reason of the reaction of the columns of water thrown off by the screws against the rudders.

At a point intermediate the extremes of the stern section, and before the elliptical form of the frames becomes exaggerated, a water-tight bulk head *l* is applied, which may be of plating or a casting sufficiently stiff and strong to resist the pressure due to any depth of submergence. This bulkhead materially assists the elliptical frames between the same and the first circular frame in stiffening the forward part of the stern section against deformation or collapse due to the pressure of submergence. The portion of the hull abaft this bulkhead is not intended to withstand the heavy pressure due to submergence, although it may be amply strong to resist the pressure to which it is subjected when the vessel is operating on the surface. If it is not desired to utilize the space behind the bulkhead *l*, the danger of the section collapsing under the pressure of submergence may be avoided by making the section non-water-tight, that is to say, by opening the section to the sea so that the pressure inside and outside will be equalized at all times. This may be effected either by providing the sections with permanent openings to admit of the water entering and leaving the sections freely, or it may be effected, when desired, by valves placed at the top and bottom of the section and controlled from other portions of the boat. It is generally preferred, however, to utilize the space in the stern section of the boat for the storage of fuel in the form of oil and the like, under which circumstances the counterbalancing of the pressure of submergence may be effected by means of the fittings illustrated in Fig. 1, whereby the fuel may be admitted to the stern section behind the bulkhead, the latter may be vented at the top and be opened at the bottom to the pressure of the surrounding water.

q represents a vent-pipe, passing from the storage compartment behind the bulkhead *l*, which vent-pipe is controlled by a suitable cock or valve *r*. The fuel is admitted to the compartment through a filling pipe *t* which is controlled by a valve *u* operated by a suitable handle *v* located within the interior of the boat. A pipe *o* communicates with the interior of the tank at one end and with the sea at the other, and is controlled by a valve *p* so as to admit or exclude the sea water from the interior of the stern section. Before submergence of the boat the valve *p* is

opened, thereby opening communication between the stern section and the sea, and in case the space is not entirely full of oil or other fuel, either one of the valves *r* or *u* in the pipes *q* and *t*, respectively, may be opened to vent the compartment and permit it to fill. When the space is entirely filled with oil and water, the valve *r* or *u* which has been opened is closed, while the valve *p* is allowed to remain opened in order to freely admit the water of submergence and equalizing the pressure on the inside and the outside of the section. This not only prevents any change in the weight of the vessel when submerged, but also absolutely precludes any danger of collapse of this portion of the hull. The propeller shafts may, of course, be run through this stern section in the usual form, 80 in stern tubes not shown.

What I claim is:

1. A submarine or submersible boat, having a hull of substantially circular cross section for the greater part of the length thereof, a stern section merging or diminishing from such substantially circular cross section through gradually flattening elliptical cross sections into a stern frame having substantially horizontal sides, a water-tight bulkhead in the forward part of said stern section, and means for admitting pressure to said stern section to counterbalance the external pressure of submergence.

2. A twin screw submarine or submersible boat, having a hull of substantially circular cross section for the greater part of the length thereof, and a stern section merging from said substantially circular cross section into a horizontal spectacle frame forming the bearings for the shaft of said twin screws, a water-tight bulkhead in the forward part of said stern section, and means for admitting pressure to said stern section to counterbalance the external pressure of submergence.

3. A twin screw submarine or submersible boat, having a hull of substantially circular cross section for the greater part of the length thereof, and a stern section merging from said substantially circular cross section into a horizontal spectacle frame forming the bearings for the shaft of said twin screws, a water-tight bulkhead in the forward part of said stern section, and a valved inlet to said stern section to admit the water of submergence thereto to balance the internal and external pressures on said stern section.

In testimony whereof I affix my signature, in presence of two witnesses.

LAWRENCE YORK SPEAR.
